F. A. APFELBAUM.
STEREOPTICON SLIDE CARRIER.
APPLICATION FILED DEC. 9, 1913.

1,116,201.

Patented Nov. 3, 1914.

UNITED STATES PATENT OFFICE.

FREDERICK A. APFELBAUM, OF NEW YORK, N. Y.

STEREOPTICON-SLIDE CARRIER.

1,116,201.

Specification of Letters Patent.

Patented Nov. 3, 1914.

Application filed December 9, 1913. Serial No. 805,660.

To all whom it may concern:

Be it known that I, FREDERICK A. APFELBAUM, a citizen of the United States, and a resident of the city of New York, borough of Manhattan, in the county and State of New York, have invented a new and Improved Stereopticon-Slide Carrier, of which the following is a full, clear, and exact description.

10 Among the principal objects which the present invention has in view are: to provide a slide having a movable member for use in conjunction with means provided in the carrier for moving said member; to provide a carrier having a plurality of pockets for holding slides, and operative means in each of said pockets for operating said movable member; and to provide a carrier having operating means of the nature mentioned, furnished with manually-operable means for actuating the same.

In the drawings: Figure 1 is a side view of a carrier and slide therefor, both constructed and arranged in accordance with the present invention; Fig. 2 is a cross section on an enlarged scale, the section being taken on the line 2-2 in Fig. 1; Fig. 3 is a section on an enlarged scale, showing the relative arrangement of and framing for a slide of the character named, said slide having a stationary and a single rotary member; Fig. 4 is a detail view on an enlarged scale, showing a fragment of the rotary member of said slide; Fig. 5 is a detail view on an enlarged scale, showing a fragment of a stationary member with which the slides are provided; Fig. 6 is a cross-section of a slide constructed and arranged in accordance with a modification of the invention, wherein two movable members are employed.

The carrier 11 is of conventional form and construction, and is slidably mounted in a guide frame 12. The two sides of the guide frame 12 are provided with openings 13. The openings 13 are preferably somewhat smaller than the openings 14 provided in the two sides of the pocketed sections usual to carriers of this type. The upper side of the pockets having the openings 14 is preferably slotted to admit to said pockets the usual photographic slides, as well as the kaleidoscopic or stereoscopic slides formed by the movable member 15 and the stationary member 16, as shown in Fig. 2 of the drawings, and by the stationary mem-

ber 16 and the two movable members in the modified type shown in Fig. 6 of the drawings.

The movable members 15 are each provided with a metallic gear toothed ring 17. The ring 17 is suitably secured to the transparent or glass member 15, the means shown in the drawings for securing the same consisting of an adhesive strip 18, which is glued to the glass and to the ring 17. The movable members 15 and stationary member 16 are mounted in a frame 20, shown best in Fig. 6 of the drawings. The movable members and the stationary member are held in spaced relation by filling rings 21, which are fixedly mounted on the stationary member to form a seat for the movable member. The stationary member 16 is preferably rectangular, as shown in Fig. 5 of the drawings, while the movable members 15 are preferably circular, as shown in Fig. 4 of the drawings. Circular recesses to receive said movable member or members, inclusive of the rings 17 carried thereby, are formed by solid sections 22 of the frame 20, which sections are slightly thicker than the movable members 15, to provide a certain freedom of movement therefor. The frame 20 overlies the sections 22 and the members 15, to form pockets to retain and guide said members 15.

The members 15 are mounted each on opposite sides of the member 16. Where one member 15 only is used, it is disposed at one side of the member 16, as best shown in Fig. 3 of the drawings. Whether one or two members 15 be used, the gear toothed ring 17 of the same engages one of the worms 23. The worms 23 are fixedly mounted on an elongated shaft 24, and are disposed directly below the centers of the openings 14 and the centers of the members 15 and 16, when the slides which they compose are dropped or placed in the pockets having said openings 14. The shaft 24 is extended lengthwise of the carrier 11 and mounted in bearings formed in the blocks 25 disposed in the runway or channel 26 which extends below said pockets. The channel 26 is extended beyond the body of the carrier, to support the end bearing block 27 at a point removed from the end of the body of the carrier.

A bracket frame 28 is extended from the end of the carrier in position adjacent to the extension of the channel 26, said bracket

frame being provided to support a bearing for the driving gear wheel 29. Fixedly mounted upon the gear wheel 29 is a crank handle 30, by means of which said wheel is 5 manually rotated. The teeth of the wheel 29 are meshed with the teeth of a small pinion 31 fixed upon the end of the shaft 24. The ratio of difference in size of the wheel 29 and the pinion 31 regulates the relative 10 speed of rotation of said wheel and the shaft 24 and worms 23 mounted thereon.

As seen in Fig. 1 of the drawings, a carrier, such as 11, being equipped with the 15 shaft 24 and driving mechanism therefor, is first furnished with slides, to be exhibited when the openings 14 therein are moved in line with the openings 13 in the frame 12. When the slide having the members 15 and 20 16 is in line with the openings 13 of the frame 12, the operator grasps the crank handle 30, and by manipulating it, rotates the shaft 24, which, through the medium of the worms 23, rotates the members 15.

As shown in Figs. 4 and 5 of the drawings, 25 the members 15 and 16 are provided with radially-disposed curved lines. These lines are preferably oppositely pitched, so that when the member 15 is rotated, the combined effect results in a centrifugal or centripetal 30 roseate development. Other shapes and varieties of colors may be used to produce different designs or kaleidoscopic effects.

When using the two members 15, as shown 35 in Fig. 6 of the drawings, the member 16 is generally ruled or figured to coöperate with both of the members, for the production of a pleasing and pre-arranged effect.

The carrier 11 is provided with a handle 32, by which it is moved in the frame 12. 40 The handle 32 is preferably pivoted by means of a pin 33 on a lug 34 set out from the end of the carrier 11. The handle 32 is thus pivoted so that it may be moved to the

vertical position as shown in the dotted lines in Fig. 1 of the drawings, and thus avoid 45 interfering with the operator when manipulating the wheel 29 and the handle 30 connected therewith.

The stop pins 19 shown best in Fig. 4 of the drawings, are provided to limit the 50 movement of the member 15 when it is desired to oscillate said member. In this movement, the pins 19, striking upon an obstruction of any suitable character placed in its path, prompts the operator to reverse the 55 movement.

Claims.

1. In combination, a slide-carrier having a plurality of pockets; a rotary shaft mounted on said carrier, below said pockets; a plurality of worm gears extending to within 60 said pockets and fixedly mounted on said shaft, one of said gears being in open communication with, and disposed in line with a radius of each of said pockets; a slide having a plurality of members relatively movable, said members engaging said worm gears when placed in either of said pockets; and means for rotating said shaft.

2. An apparatus as characterized, comprising a slide embodying a stationary member; a rotary member; a gear-toothed ring fixedly mounted on said rotary member, said ring extending below said stationary member; and a frame slidably supporting said 75 ring, for maintaining the same in line with said stationary member, said frame having an opening at the edge thereof to expose said ring.

In testimony whereof I have signed my 80 name to this specification in the presence of two subscribing witnesses.

FREDERICK A. APFELBAUM.
